[57] CLAIM

The ornamental design for a tire tread, as shown and described.

DESCRIPTION

FIG. 1 is a perspective view showing the tire tread; FIG. 2 is a front elevational view thereof; FIG. 3 is a side elevational view thereof; and, FIG. 4 is an enlarged fragmentary view of a portion of the tire tread as illustrated in FIG. 2.

The broken line showing of the tire sidewall in FIGS. 1 and 3 of the drawing is for illustrative purposes only and forms no part of the claimed design.

FIG-1

FIG-2

FIG-3

FIG-4
